Des. 436

I. Harvey Conklin, of Peekskill, N.Y.
assignee to
W. D. & J. Vredenburg
Letters Patent No 436, Dated, Jan'y 6. 1852.

The Schedule referred to in these Letters Patent and making part
of the same.

To all whom it may concern:

Be it known,
that I, I. Harvey Conklin, of Peekskill in the county of
Westchester & State of New York, have invented a new & ornamental
design for stoves, and I do hereby declare that the following

is a full, clear & exact description of the same, reference being had to the accompanying drawings, forming part of this specification in which -

Fig. 1., is a front view or elevation, the side doors being removed. -

Fig. 2., is a side elevation in part, not exhibiting the front plate & doors seen in fig 1. -

Fig. 3., is a horizontal section in part of the front plate and door taken, as indicated by the line 0, 0, fig 1.

Fig. 4., is a similar section of one of the side doors intersecting the same, as indicated by the line 1, 1, fig 2.

Fig. 5., is a further section, cutting the side plate & one of the panels as shown by the line 2, 2, fig 2.

Fig. 6., 3, 4, and 5, representing the profiles of the several mouldings surrounding the ornaments on the doors & panels and the same letters of reference denoting the several parts throughout the several figs.

The novelty of my ornamental design consists in the configuration & arrangement of the several parts which referring to the drawings, I shall proceed to describe.

The front plate of the stove has a slightly curved, that is convex panel or projecting surface A (fig 1) at its top which serves to carry the title as seen in fig 1- by name of "the Invincible air tight" and which has a raised ornament B, (one at either end) consisting of a fanciful device a, bearing two scrolls, somewhat resembling the figure of 8, from or at one end of each, branching to either side an stems b, b, having floral & other scroll work attached, as exhibited in the drawing. - The front plate of the stove down either side near the ends where the front doors C, D, are hung is provided with a moulding, having a fillet c, as seen more clearly in fig 3, which exhi-

bites also the profile of the moulding, marked d, e, f. (figs 1, 83) surrounding the centre panel of each door C D made with a swinging joint or hinge h; the centre panel of each said door having a raised ornament E thereon (fig 1) which consists of a central ornament g, having curved stems i, i, on either side carrying floral & other scroll devices as represented.

F, is the top, G, the bottom, and H (fig 2) one of the side plates which latter is bounded by a moulding marked j, k, (figs 2 and 5) seen within which near one of the lower corners, is a raised ornament I, made up of similar scroll & leaf devices at either side & having above and below it dissimilar ornamental projections (as seen in fig 2) —

J, is a panel on one of the side plates, of trapezoidal form, situated above the ornament I that is at the front upper corner of the plate H, it is bounded by a moulding marked l, m, m, (figs 2 & 5) and has raised upon it within the moulding a leaf or floral ornament K (fig 3) the panel I, with its moulding and ornament as described is or may be made fast only on one side of the stove & construction loose on the other side does to form a door —

L, is a side door (the same being on either side of the stove) also of trapezoidal form, bounded by a moulding marked o, p, q, (figs 2 & 4) consisting of fillets, beads, hollow & round, whose configuration is shown more clearly by the profile seen in fig 4, the central panel of the door carrying a floral scroll device or raised ornament M, fig 2 —

N, figs 4 & 2, is one of the legs & feet of the stove which are made of ornamental design as represented, consisting of a shield n, at the top,

mounted by globes 588 and having attached to it a
drop 6 at the bottom, bounded on either side by curved
indented surfaces or scalloped projections t, t , and
the remainder of the leg to the foot being formed of curved
or indented projections or surfaces ending in tors u, u
as shown by front view in fig 2, and profile in fig 1.

What I claim as my Invention I desire
to secure by Letters Patent is,

The Configuration & design of the several
ornaments & their mouldings particularized
on the front sides doors legs and feet of the
stove formed and arranged as depicted and
described.
